UNITED STATES PATENT OFFICE.

JAMES M. ALLEN, OF ST. LOUIS, MISSOURI, ASSIGNOR OF ONE-TENTH TO WALTER A. GRUENEWALD, OF ST. LOUIS, MISSOURI.

HYDROCARBON-ENGINE.

1,137,446.

Specification of Letters Patent. Patented Apr. 27, 1915.

Application filed December 5, 1913, Serial No. 804,886. Renewed March 18, 1915. Serial No. 15,390.

To all whom it may concern:

Be it known that I, JAMES M. ALLEN, a citizen of the United States, and resident of St. Louis, Missouri, have invented certain new and useful Improvements in Hydrocarbon-Engines, of which the following is a specification containing a full, clear, and exact description, reference being had to the accompanying drawings, forming a part hereof.

My invention relates to improvements in hydrocarbon engines, and consists in the novel construction hereinafter described and specifically designated in the appended claims.

The object of my invention is to provide an improved "twin cylinder" hydrocarbon engine which shall have a single compression chamber of ample size connected to a plurality of cylinders.

A further object of my invention is to provide an improved hydrocarbon engine with "twin cylinders" each having a piston therein, and a single connecting rod arranged to convey power of both pistons to a single crank.

In the drawings Figure 1 is a vertical section taken through my improved hydrocarbon engine on the line 1—1 of Fig. 2. Fig. 30 2 is a sectional plan view of the engine with parts broken away; Fig. 3 is a detail sectional view of a portion of the cylinder-head showing the arrangement of one of the valve-seats; Fig. 4 is a front elevation of 35 the engine; and Fig. 5 is a sectional plan view taken through the lower portion of the cylinders on the line 5—5 of Fig. 4.

My invention may be applied to either the "four cycle" or "two cycle" form of 40 engine, the former being shown in the present drawings.

The numeral 1 indicates the usual crank-case having mounted therein a crank-shaft 2 carrying the usual fly-wheel 3.

45 Mounted upon the upper portion of the crank-case 1 is a plurality of "twin" cylinders 4, which extend parallel and each cylinder is separated from its twin by a partition-wall 5 which extends from the compression-space 6 toward the crank a considerable 50 distance, but not sufficiently far to prevent a single cross-head 7 from straddling said partition-wall and directly connecting the twin pistons 8. The cross-head 7 is bifurcated at its upper end, and the forks there-

of are extended upwardly within said twin-pistons and secured therein by the bolts or rivets 9, which pass through the over-lapping parts. A single connecting-rod 10 connects said cross-head pin 11 to a single 60 crank 12 of said crank-shaft 2. A single compression-chamber 6 connects the interior of the said cylinders 4, at the upper ends of the latter.

It will be observed that the forks of the 65 bifurcated cross-head 7 straddle the lower end of the said partition wall 5 when the pistons are at the end of their upward stroke, said partition wall being limited in its length for this purpose.

There may be as many twin cylinders as the work requires, I having shown in the present instance two twins mounted on a single crank-case, but it is obvious that the 70 number of twins may be increased or diminished according to the work required of the engine. The said pistons 8 are provided with the usual packing-rings 13, and the upper portions of the twin cylinders are 75 provided with the usual water-jacket 14.

The numeral 15 indicates a common cylinder-head which is provided with the usual water-jacket 16 and extends across the compression-space 6 of both cylinders composing a twin, so that there is but a single cylinder-head for the twin cylinders.

The valves and valve-gear of my improved engine may be of any ordinary construction, although in the present case I have shown the valve-casings 17 formed integral with the cylinder-head 15, and suitable cams 18 for operating the valve-stems 19, said cams being driven by the usual sprocket-wheels 20 connected by a sprocket-chain 21 to an intermediate shaft 22, driven 90 at half the speed of the crank-shaft by means of suitable sprocket-wheels 23 and 24 and a sprocket-chain 25, said shaft 22 being mounted in suitable bearings 26.

The operation of my improved hydrocarbon engine and its advantages will be readily apparent to those skilled in the art and need not be described in detail.

I claim:

1. The improved hydro-carbon engine, 105 comprising twin parallel cylinders, twin pistons in said cylinders, a partition-wall separating said cylinders and limited in length, a crank-shaft, a bifurcated cross-head having vertical forks which are ex- 110

2
tended upwardly within said pistons astride of said limited partition-wall, to directly connect said twin pistons at the points of their connection with said forks, a cross-head pin carried by the lower end of said cross-head, and a single connecting-rod extending from said cross-head pin to said crank-shaft.

5 2. A hydrocarbon engine having a number of pairs of parallel twin cylinders arranged on a single crank-shaft, pistons in each pair of said cylinders, a partition-wall separating the compression end of each pair of cylinders, bifurcated cross-heads

straddling the said partition-walls, a cross-head pin at the lower end of each cross-head, a single compression-space connecting the cylinders of each pair, a crank-shaft having a number of cranks formed thereon, and a connecting-rod attached to each cross- 20 head pin and to said crank-shaft.

In testimony whereof, I have signed my name to this specification, in presence of two subscribing witnesses.

JAMES M. ALLEN.
